(57) **CLAIM**

The ornamental design for an operating and display panel for elevators, as shown and described.

DESCRIPTION

FIG. 1 is a front view of an operating and display panel for elevators showing our new design;

FIG. 2 is a front view of a second embodiment thereof;

FIG. 3 is a front view of a third embodiment thereof; and,

FIG. 4 a front view of a fourth embodiment thereof.

The oblique shade lines in the figures show transparency.
